UNITED STATES PATENT OFFICE.

JOSEPH M. SCHNEIDER, OF CANTON, OHIO, ASSIGNOR OF ONE-HALF TO
ELMER HICKS, OF SAME PLACE.

GATE-LATCH.

SPECIFICATION forming part of Letters Patent No. 576,280, dated February 2, 1897.

Application filed June 8, 1896. Serial No. 594,664. (No model.)

To all whom it may concern:

Be it known that I, JOSEPH M. SCHNEIDER, a citizen of the United States, residing at Canton, in the county of Stark and State of Ohio, have invented certain new and useful Improvements in Gate-Latches; and I do hereby declare that the following is a full, clear, and exact description of the same, reference being had to the annexed drawings, making 5 a part of this specification, and to the letters of reference marked thereon, in which—

Figure 1 is a view showing the latch proper and applied to a gate. Fig. 2 is a vertical section of the housing, showing said housing 15 properly connected to a post and illustrating the gravity-ring. Fig. 3 is a perspective view of the latch. Fig. 4 is a transverse vertical section of the latch, showing the gravity-ring properly attached thereto and illustrating 20 the catch-bar in relative position. Fig. 5 is a detached perspective view of the catch-bar.

The present invention has relation to gate-latches; and it consists in the different parts and combination of parts hereinafter 25 described, and particularly pointed out in the claim.

Similar letters of reference indicate corresponding parts in all the figures of the drawings.

30 In the accompanying drawings, A represents a gate, which is properly hinged to a post, such as *a*, and may be of any desired style or kind, inasmuch as the gate within itself forms no particular part of the present 35 invention.

To the free end of the gate is attached in any convenient and well-known manner the catch-bar *B*, which catch-bar is provided with the curved flange or arm *b*, said curved flange 40 or arm being for the purpose hereinafter described.

The housing *C* is preferably formed integral with the attaching-bar *d*, which bar is securely connected to the post *d'* or its equivalent. For the purpose of providing a means 45 for adjusting the housing *C*, together with the gravity-ring *D*, up or down the attaching-bar *d* is provided with the elongated slots *d'*, through which elongated slots are passed the 50 lug-bolts *e* or their equivalents. The object

and purpose of providing the housing *C* is to protect the gravity-ring *D*, so that its movements will not be interfered with by the accumulation of snow and ice, thereby leaving said ring free at all times and in all kinds of 55 weather. The gravity-ring *D* is connected to the housing *C* by means of the cross pin or bar *f*, said cross pin or bar being located to one side of the vertical center of the housing, and is so located for the purpose of normally 60 holding the gravity-ring *D* away from the attaching-bar *d*, thereby allowing the ring to remain in its normal position when the catch-bar *B* is placed between the ring and the attaching-bar *d*, as illustrated in Fig. 1. 65

In use, when it is desired to open the gate, the gravity-ring *D* is elevated, which movement releases the catch-bar *B* and allows the gate *A* to turn upon its hinges. After the catch-bar has passed the ring *D* said ring will 70 fall by its own weight until it assumes the position illustrated in Fig. 3. As the gate is closed the catch-bar *B* will come in contact with the outer portion of the ring *D* and elevate said ring, so as to allow the catch-bar to 75 pass under the same, and when said catch-bar has passed the vertical center of the ring said ring will drop downward and in front of the catch-bar. The gate will be held in a closed position by reason of the ring *D* coming in contact with the outer inner edge *g* of the housing *C*; but by reason of the ring *D* being suspended to one side of the vertical center of the housing said ring will be free 80 to be elevated when the catch-bar presses 85 against the outer portion of the ring.

I have illustrated the present invention as applied to gate-latches, but it will be understood that it may be applied to other devices turning upon hinges without departing from 90 the nature of my invention.

The curved arm *b* is for the purpose of providing a means for pulling the gate open after the ring has been elevated, and is so located that a finger of the hand can be passed 95 under said curved arm, which brings the finger in proper position to elevate the ring and free the gate or other device to which my improved latch may be attached.

Having fully described my invention, what 100

I claim as new, and desire to secure by Letters Patent, is—

The combination of the catch-bar B, provided with the curved flange or arm b, the 5 housing C, provided with the attaching bar or rib d, having the elongated slots d², the ring D, and the cross bar or pin f, all arranged substantially as and for the purpose specified.

In testimony that I claim the above I have hereunto subscribed my name in the presence 10 of two witnesses.

JOSEPH M. SCHNEIDER.
